UNITED STATES PATENT OFFICE.

HOWARD STILLMAN, OF BERKELEY, CALIFORNIA.

CAR-BRAKE.

1,100,270.

Specification of Letters Patent. Patented June 16, 1914.

Application filed February 25, 1914. Serial No. 820,834.

To all whom it may concern:

Be it known that I, HOWARD STILLMAN, of Berkeley, in the county of Alameda and State of California, have invented a certain new and useful Improvement in Car-Brakes, of which improvement the following is a specification.

My present invention particularly relates to means for manually effecting the application of brakes on railroad cars, and is an improvement on that for which Letters Patent of the United States No. 1,034,659, were granted and issued to me under date of August 6, 1912.

The object of my invention is to provide an appliance in the operation of which the useful results of that set forth in my Letters Patent No. 1,034,659 aforesaid, may be fully attained, with a simplification of mechanism and a resultant reduction of the cost of construction and maintenance.

The improvement claimed is hereinafter fully set forth.

In the accompanying drawings: Figure 1 is a view, in elevation, of the blind end of a mail or baggage car, illustrating an application of my invention; Fig. 2, a horizontal section through the same; Fig. 3, a front view, on an enlarged scale, of the ratchet mechanism; and, Fig. 4, a longitudinal central section, on a similar scale, through the supports of the ratchet mechanism, with the latter in elevation.

My invention is herein, as in Letters Patent No. 1,034,659 aforesaid, exemplified in connection with the ordinary means of manually applying brakes in the inside of a car body, 1, at the blind or non-vestibuled end thereof, the same consisting of a hand wheel, 2, indicated in dotted lines in Fig. 1, having its shaft, which is journaled on a suitable member of the car frame, connected to a brake chain, 3, which is wound on the shaft by the rotation of the hand wheel, and passes therefrom, around sheaves, 4 and 5, to the brake rigging, which may be of any of the well known forms, and, as it does not, in and of itself, form any part of my present invention, is not shown.

In the practice of my invention, for the purpose of enabling the brakes to be applied and released, when required, from the outside of the car, while the latter is in motion, I provide a horizontal brake chain shaft, 6, the inner end of which is journaled in a bearing 6^c, adjacent to the end of the car

at which the shaft of the usual hand wheel, 2, is mounted, and which projects outwardly through the end of the car. The outer bearing, 6^a, of the brake chain shaft, is formed on an integral bearing and stop plate, 60, which is riveted or bolted to one of the end plates of the car body, 1, and its inner bearing, 6^c, is cast on a standard secured to the under frame of the car, and the brake chain shaft is connected to a brake chain, 7, which, in its rotation, is wound upon it, and which passes around sheaves, 8 and 9, to the brake rigging, in the same manner as the brake chain of the usual hand wheel.

A combined operating and locking ratchet, 6^a, is fixed upon the brake chain shaft, 6, on the outside of the car and adjacent to the outer bearing, 60^a, of the shaft, which is turned in direction to wind the brake chain 65 upon it and set the brake, by a ratchet lever, 10, journaled on its outer end, said lever carrying an operating pawl, 10^a, which oscillates upon a pin on the ratchet lever, and is normally engaged with the teeth of the 70 ratchet, 6^a, by a spring, 10^b. A lateral releasing dog or projection, 10^c, formed on the pawl, 10^a, is adapted to abut against a stop, 60^c, formed integral with the bearing and stop plate, 60, when the ratchet 75 lever is moved into the position shown in the drawings, in which position it abuts against a lever stop, 12, fixed to the car end, the pawl, 10^a, being thereby disengaged from the teeth of the ratchet, 6^a.

A stud, 13, is fixed in a sleeve, 60^d, on the bearing and stop plate, 60, and a double armed locking and releasing lever, 13^c, 13^d, is pivoted on said stud. The lower arm, 13^c, of the lever, is weighted on its outer end, 95 sufficiently to normally maintain a locking pawl, 13^b, which is formed or fixed on its upper arm, in engagement with the teeth of the ratchet, 6^a, and thereby to lock the latter, that is, to prevent its rotation with the 100 brake chain shaft, 6, on which it is fixed, in direction opposite to that imparted by the movement of the ratchet lever, 10, away from the lever stop, 12. The upper arm, 13^d, of the locking and release lever, projects beyond the pawl, 13^b, and is curved toward the ratchet lever, 10, and made of such length as to be contacted with and moved by said lever, when the latter is brought up to or near the stop, 12, and thereby to release 110 the locking pawl, 13^b, from the ratchet, 6^a.

In the operation of the appliance, the

2
brakes are set and released by a brakeman riding on the side step, 14, of the car, in a similar manner to the operation of the brake mechanism of Patent No. 1,034,659 afore-
5 said, and it will be seen that this result is accomplished by my present construction with the elimination of the long pawl shaft, 13, its inner bearing, 13^a, and the independent locking ratchet, 6^b, of said patent. A
10 further advantage attained by my present construction is the provision of an outer bearing for the brake chain shaft of materially greater length than is obtainable in the comparatively thin plate metal of the
15 car, and the formation of said bearing, the support for the locking and release lever, and the releasing stop for the pawl of the ratchet lever, in an integral casting.

I claim as my invention and desire to set
20 cure by Letters Patent:

1. The combination, with a railroad car, of a brake chain shaft, a brake chain extending therefrom to a connection with the brake rigging of the car, an integral bearing
25 and stop plate secured to an end of the car body, a ratchet fixed on the brake chain shaft, a ratchet lever journaled on said shaft outside the car body, a pawl coupled to said lever and adapted to engage the ratchet, a
30 releasing dog on said pawl adapted to abut against a stop on the bearing and stop plate a double armed locking and release lever journaled on the bearing and stop plate adjacent to the brake chain shaft, and a pawl

on said lever adapted to engage the ratchet 35 in opposite direction to the pawl of the ratchet lever.

2. The combination, with a railroad car, of a brake chain shaft, a brake chain extending therefrom to a connection with the brake 40 rigging of the car, an integral bearing and stop plate secured to an end of the car body, a ratchet fixed on the brake chain shaft, a ratchet lever journaled on said shaft outside the car body, a pawl coupled to said lever 45 and adapted to engage the ratchet, a releasing dog on said pawl adapted to abut against a stop on the bearing and stop plate and a double armed locking and release lever 50 journaled on the bearing and stop plate adjacent to the brake chain shaft, said lever carrying a pawl adapted to engage the ratchet in opposite direction to the pawl of the ratchet lever and having one of its arms in position to contact with said lever at one 55 extremity of the traverse thereof.

3. In a car brake, the combination of a bearing and stop plate having integral therewith a bearing for a brake chain shaft, a pawl releasing stop, and a support for a 60 locking and release lever; a brake chain shaft journaled in the bearing, and a locking and release lever pivoted on the lever support of the bearing and stop plate.

HOWARD STILLMAN.
